UNITED STATES PATENT OFFICE.

WILLIAM SCHEUERMAN, OF LEOTI, KANSAS.

RAIL-BRACE.

1,093,482.

Specification of Letters Patent. Patented Apr. 14, 1914.

Application filed October 30, 1913. Serial No. 798,345.

To all whom it may concern:

Be it known that I, WILLIAM SCHEUERMAN, a citizen of the United States, residing at Leoti, in the county of Wichita, State of Kansas, have invented certain new and useful Improvements in Rail-Braces; and I do hereby declare the following to be a full, clear, and exact description of the invention, such as will enable others skilled in the art 10 to which it appertains to make and use the same.

This invention relates to rail braces and has for an object to provide a brace that will positively hold both rails of the track 15 against relative displacement.

A further object of the invention is to provide a rail brace that will prevent overturning of the rails and will prevent spreading of the rails outwardly or moving of the 20 rails inwardly, such means being formed of a few simple and inexpensive parts that will be strong and durable and will not easily get out of order.

With the above objects in view the invention 25 consists of certain novel details of construction and combination of parts herein-after fully described and claimed, it being understood that various modifications may be made in the minor details of construction 30 within the scope of the appended claim.

In the accompanying drawing illustrating 35 this invention:—Figure 1 is a plan view showing the application of my invention. Fig. 2 is a horizontal sectional view through the webs of both rails showing the manner in which the parts grip the rails. Fig. 3 is a cross sectional view on the line 3—3 Fig. 1. Fig. 4 is a cross sectional view on the line 4—4 Fig. 1.

Referring now to the drawing in which like characters of reference designate similar parts, 10 designates railway track rails and 11 the railway ties. The brace comprising the subject-matter of this invention consists 40 of a pair of hooks 12 the shanks of which are threaded respectively right and left hand as shown at 13 and joined together by a turn buckle 14. The hooks are designed to hook over the outer edges of the base flanges of

both rails whereby upon tightening of the 50 turn buckle the hooks will be drawn toward each other and positively prevent outward spreading of the rails.

A brace bar 15 of sufficient length to bear 55 upon the base flanges of both rails and terminally engage the inner faces of the webs of both rails, is disposed in advance of and parallel with the threaded hooks 12. This brace is equipped near the ends with strap iron links 16 which are riveted or otherwise 60 secured to the brace and bear with the outer edges against the inner edges of the adjacent base flanges of the rail, each link being given a half twist intermediate its ends as shown at 17 to dispose the end most remote 65 from the brace in a vertical plane, such end being equipped with an opening 18 through which the related hook 12 passes. This brace holds the rails positively against inward relative movement, the links 16 preventing 70 the inner ends of the hooks from dropping down, thus a portion of the weight of the turn buckle being supported by the brace so that distortion of the parts is prevented.

From the above description it will be seen 75 that I have provided an extremely simple and inexpensive brace which will positively prevent relative displacement of the rails and will furthermore be formed of a few strong and durable parts that will not easily 80 get out of order.

What is claimed, is:—

A rail brace including a pair of hooks engageable over the outer edges of both rails of a track, a turn buckle connecting the inner 85 ends of said hooks between the rails, a brace parallel with said hooks and having endwise engagement with the inner faces of the webs of said rails, and a pair of parallel links carried by said brace and engaging said hooks 90 between said rails whereby the inner ends of said hooks are supported by said brace.

In testimony whereof I affix my signature in the presence of two witnesses.

WILLIAM SCHEUERMAN.
